BUMPER AND BRUSH BODY

William C. Otto, Indianapolis, Ind., assignor to
 J. I. Holcomb Manufacturing Company, Indianapolis, Ind., a corporation

Application October 24, 1940, Serial No. 362,534.

4 Claims. (Cl. 15—159)

This invention relates to brushes broadly of the type illustrated in the Otto Patent No. 2,177,149 dated October 24, 1939.

This invention is directed to a brush structure and relates more particularly to the provision of a bumper attachment included in and at the ends of an elongated brush of the character before mentioned.

The chief object of this invention is to provide a bumper construction and mounting arrangement which is peculiarly applicable to any one of the three standard types of brush structures and which bumper construction when sufficiently worn may be removed and readily replaced with a similar bumper.

The chief feature of the invention consists in providing the bumper arrangement as a cap structure which is peculiarly associated with and mounted upon a brush back as hereinafter pointed out more fully.

Other objects and features of the invention will be set forth more fully hereinafter.

The full nature of the invention will be understood from the accompanying drawings and the following specifications and claims.

In the drawings,

Fig. 1 is a side elevation of slightly more than half of a brush body, a portion of the back structure being broken away to show the same and the bumper in greater detail, the brush body being of the wire drawn type.

Fig. 2 is a similar view of a brush body of the pitch set type.

Fig. 3 is a top plan view of the end portion of the brush body with bumper cap omitted therefrom, as illustrated in Fig. 1.

Fig. 4 is a similar view of the same with the bumper cap mounted thereon.

Fig. 5 is an inside perspective view of the bumper cap.

Fig. 6 is a longitudinal sectional view of a modified form of cap.

Fig. 7 is a top plan view of the same.

Fig. 8 is an end elevation of a modified form of cap looking at the brush receivable end.

Fig. 9 is a bottom plan view thereof.

Fig. 10 is a view similar to Fig. 8 and of a modified form of cap.

Fig. 11 is a bottom plan view thereof.

Fig. 12 is a top plan view of the brush body adapted to receive the cap shown in Figs. 10 and 11.

The brush structure is of the general character illustrated in the before mentioned patent—that is, it includes a group of bristle tufts mount-

ed in and upon an elongated brush back provided with one or more anchoring portions adapted for handle connection, the latter being clearly described in the before mentioned patent and the same forms no part of the present invention. If desired, any other convenient handle arrangement may be provided for associating the handle and brush body together.

As set forth in the before mentioned patent, 10 brushes may be of three types insofar as the bristle mountings thereon are concerned. One type shown herein in Fig. 2 is of solid back type and briefly includes a hole in which bristles of the length of the tuft are assembled in group 15 forming tufts and are inserted in said hole and locked therein by means of pitch or other suitable adhesive.

The other broad type is the wire drawn type 20 wherein the brush back is parted and the bristles are arranged in tufts but of a length double that of the tuft length and the bristles are doubled upon themselves. The wire is associated with the midportion of the bristles at the back seated end of the tuft and the wire is associated with 25 the back, more particularly as shown in Fig. 3 of the before mentioned patent. This requires, as shown in Fig. 1 of said patent and as shown in Fig. 1 herein that the brush back be parted.

A third and intermediate type of brush is one 30 wherein the tuft is formed by doubling the bristles upon themselves and the midportion is associated with a staple which is driven into the brush back and each staple associated end of the tuft is seated in an opening formed in the solid back portion of the brush body. Herein the term 35 "brush body" is intended to include the entire bristle arrangement together with the back structure. The term "brush back" is intended to comprehend the bristle supporting portion of the 40 brush body and not the bristle formation.

With this brief explanation of the several types of bristle mountings conventional to the industry, reference now will be had to the drawings.

In Fig. 1 of the drawings 10a indicates the 45 upper part of a two-piece back structure, 10b indicates the lower part thereof, the two being suitably secured together as by the securing means 11, herein shown in the form of screws. They may, however, be bolts and nuts, such as 50 illustrated in Fig. 1 of the before mentioned patent, in which event the bolt will extend entirely through the two brush back forming elements and the head will be countersunk and the nut will be concealed by the bristle structure 12. The latter, similar to that illustrated in the before

mentioned patent, is flared outwardly in all directions from the body portion.

Herein 12a designates a bristle tuft arrangement and 13 indicates a hole properly positioned with respect to other holes in the portion 10b and at the proper angular relation to said back structure to secure suitable bristle distribution and direction. These openings 13 extend entirely through portion 10b and the wire associated with the midportion of the bristles and the anchoring end of the tuft is connected thereto in the conventional manner and to other tufts, all as shown in Fig. 3 of the before mentioned patent.

Referring to Figs. 1 and 3, it will be noted that there is a parting in the brush back designated as 10c. There is provided in this brush back structure at each end a slot 14 which is positioned intermediate the top and bottom of the brush back as shown in Fig. 1. Inasmuch as the end 15 of the brush back is rounded from top to bottom, this slot formation 14 provides a tongue portion 15a at the end 15 of the brush back and that tongue portion terminates short of the end 15. The slot 14 is directed toward the center of the brush as at 14a along the opposite sides of the brush or the front and back of the brush body portion and said slot extensions terminate as at 14b adjacent the end 15, reference being had to the center of the brush.

The center of the brush includes suitable apertures 16 which intersect and are threaded to reversibly receive a handle element 17. This arrangement is more fully illustrated in the before mentioned patent and the same forms no part of the present invention.

Herein the slot 14 with its extensions 14a terminating at 14b is formed by entirely kerfing the end 15, as shown, this resulting in the slot 14 having its ends 14b coincident with the back portion 14c of the slot 14. Preferably this kerfing or slotting all is provided in the portion 10a, leaving the portion 10b unmodified and all available for tuft mounting purposes.

Furthermore, this arrangement permits owners of conventional, elongated wire drawn brushes to purchase the bumper caps, herein to be more fully described, and the major part of the invention, and apply the same to such standard brushes of this character by merely separating the two brush back portions from each other and properly shouldering the lower face of the upper portion to the extent noted. In other words, the slot formation formed by this shouldering does not in any way disturb the previous bristle mounting arrangement.

Reference now will be had more fully to Figs. 1, 3, 4 and 5, wherein except for Fig. 3, the bumper cap is illustrated. This bumper cap includes an end wall arrangement 20, and two side portions 21 joined thereto as by merging therewith as at 21a. The two side portions 21 and the end wall 20, as well as merging portions 21a form a skirt and at their top edges all are connected together by the retaining portion 22, the latter forming a tongue for the purpose hereinafter described. It is to be noted that the portion 20 is considerably thicker as indicated at 20a in Fig. 5. The inside face 20, the inside faces of the side walls 21 conform to the side wall portions at the end 15 and the end wall of the brush body portion 10b.

The cap connecting portion 22 forming the tongue is adapted to be slidably and longitudinally inserted in the slot formation 14-14a. The edge 22a thereof is adapted to engage the wall

or shoulder designated by 14b and 14c in Fig. 4. Rubber cement or other suitable adhesive may be applied to a portion of the top 22 of the bumper cap structure shown more clearly in Fig. 5, and to the inside of said cap structure so that when the cap is slidably mounted upon the brush back and held under slight pressure thereto, the bumper cap is suitably secured to the brush back. The resulting structure is a bumper guard arrangement of cap character, which, however, leaves the upper and lower faces, as it were, of the brush back exposed.

By reason of the taper or rounding end 15a of the brush back, and as shown more clearly in Fig. 4 as well as Fig. 1, the cap structure protects the end of the brush and thus in its use prevents marring of articles of furniture by reason of brush end engagement. This cushion-like cap is also a silencer. In other words, sweeping can be performed without objection at such times and in such places where noise of brush end contact would normally be objectionable.

Whenever the bumper guard becomes sufficiently worn, it may be readily removed by merely severing the side portions and the end from the top portion and separating the same from the body portion 10b at the end 15 and then the cap portion may be suitably removed by a rekerfing operation if the brush back be of solid type or may be readily removed by separating the two brush back portions and then inserting a sharp bladed instrument between the portion 22 and the upper back portion 22 adheres to the back portion 10b, it may be readily peeled therefrom, all without disturbing the wire anchorage arrangement which then is exposed following the peeling operation. The brush parts then are reassembled and replacement caps provided.

If desired and the same is contemplated within the scope of this invention, the thickness of the portion 22 may be slightly greater than the thickness of the slot 14 and the distance between the side wall portions may be slightly less than the width of the brush body portion 10b at the end.

Since the bumper cap structure is of resilient material, such as rubber, it will be quite apparent that in this arrangement the bumper cap may be slipped into the slot and thus mounted and the same will be frictionally retained on the back with sufficient force to prevent casual disconnection.

Reference now will be had to Fig. 2. In Fig. 2 numerals of the 100 series indicate like or similar parts. Herein it will be observed that the brush back 110 is of solid type and it is to be understood that there is provided in the brush back recesses 113 which receive the bristles or tufts 112a and the same are secured in said recesses by pitch for a pitch set brush or staples by a staple set brush. It is to be observed, however, that the end tufts have the recesses 113 terminating below the adjacent plane of the slot 114 which receives the body portion 122 of the cap structure having the end portion 120 and the side wall portions 121.

As previously set forth, the thickness of the portion 122 of the cap as contrasted with the thickness of the slot 114 may be such that a friction lock arrangement may be provided therebetween. Likewise, the distance between the side walls 121 may be such as to be but slightly less than the width of the end 115 of the elongated brush back so that said side walls 121 will fric-

tionally engage the same. If desired, suitable adhesive such as rubber cement or the like, may be provided to permanently, relatively speaking, secure the cap to the brush end.

By means of this cap structure, as previously set forth, the end of the brush and more particularly that portion adjacent the bristle mounting portion, is protected against damage and thus the end bristles or body of the brush will not become loosened, and the like, resulting in brush damage. Furthermore, this particular type of cap structure has the additional desirable advantage that it protects furniture legs and the like, mop boards, door casings, and the like, from being marred by reason of contact with the brush end.

As previously pointed out, with both types of brush structures, the same being dissimilar only in the respects noted, the emergence of the side walls of the cap as at 21a and the body portion 22 as well as the end wall portion 20 is such that the immediate end of the brush is protected even though a part of the brush at the end is relieved. Thus, the top of the brush at the immediate end is protected and yet the immediate top of the brush is fully exposed for advertising and other matter, if desired.

In Figs. 6 and 7 there is illustrated a modified form of cap structure and numerals of the 200 series indicate like or similar parts herein, which are similarly indicated by the primary and 100 series in the other figures.

The chief distinction herein is the provision of a serrated portion on either or both faces of portion 222. Herein same is shown at 222a and 222b on both faces and the teeth are staggered so that when forcibly inserted in a slot 14 or 114, the ratchet type teeth readily deform or yield to facilitate as well as permit such entrance but when an attempt is made to withdraw the tongue portion 222 from the slot 14 or 114, said teeth friction grip and resist such attempt.

Note that by offsetting or alternating the teeth on opposite faces of portion 222, the tooth formation is such that the depth of one tooth is the readily compressible portion and the thickness of the portion 122 between the root of one tooth and the opposite face is the more resistant portion, although even that, when of rubberlike material has some resiliency.

The resulting cap, therefore, is of friction retainable character, and readily mountable but difficultly demountable as well, thereby preventing casual or accidental separation incident to normal brush use.

Figs. 8 and 9 illustrate a modified form of the invention similar to those previously illustrated. Herein, numerals of the three hundred series indicate like or similar parts.

This form of the invention is characterized by the addition of an underlip 300 coextensive with the side and end walls of the cap. Herein, also, the side walls 321 instead of being substantially equidistant from front to rear, are arranged in converging relation as indicated at 301 partially at the free, hipped or rimmed portions so that when applied to the brush body these portions yield outwardly but in so doing, exert a clamping force upon the opposite sides of the brush.

As shown in Figs. 4 and 7, the free outer edge portion may be beveled or tapered. Herein the same is indicated at 302 and the lip or rim 300 adjacent bevel 302 may be tapered or beveled as at 302a.

In Figs. 10 and 11, there is illustrated a modi-

fied form of cap. In Fig. 12, there is illustrated a brush body end modified for cap mounting. The brush body A of any one of the three brush types is reduced as at B on its upper and merging side faces, said reduction extending to the end. Sockets can be drilled radially therein.

The cap shown in Figs. 10 and 11 is designated by numerals of the four hundred series. It is similar to that shown in Figs. 3, 4 and 5 except it has the curved formation D including surfaces D' and D² to correspond with the top curvature original shape and modified shape of the brush body end respectively. Bosses 406 apertured at 407 may receive screws. The outer free ends of the side walls 421, as well as free ends of lip 400 at 402a, may be tapered if desired.

When this cap is mounted, lips 400 underlie the brush face from which project the bristles. The remainder of the cap covers the end, sides 20 and top of the brush and bosses 406 seat in sockets C. Screws, not shown, then detachably secure this cap to the brush, although it is observed that screws are not absolutely essential for anchorage, since the bosses prevent rotation and longitudinal separation between cap and brush body while the rim prevents rotation.

If Fig. 9 be compared with Fig. 7, the side wall taper is apparent. Accordingly, side walls 421 in Fig. 11 may be similarly drawn inwardly whenever desired.

While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. A brush and bumper structure including a considerably elongated brush body having a back provided with a slot at each end only and between the top and bottom thereof, each slot extending along each side toward the midportion of the back but terminating immediately adjacent the end, and a cap at each end and of resilient material and having a body portion seated in the slot and a depending skirt covering the exposed end of the back as well as the sides thereof immediately adjacent the end.

2. A brush and bumper structure including a considerably elongated brush body having a back provided with a slot at each end only and between the top and bottom thereof, each slot extending along each side toward the midportion of the back but terminating immediately adjacent the end, and a cap at each end and of resilient material and having a body portion seated in the slot and a depending skirt covering the exposed end of the back as well as the sides thereof immediately adjacent the end, said cap body portion and depending skirt forming a chamber having two transverse adjacent and communicating openings, one for brush back portion reception and the other for bristle projection, said cap being slidably mounted upon the back portion at the end, the skirt protecting the opposite sides of the brush back at that end, as well as the immediate end of the brush, the brush back end being rounded, said connecting cap body portion protecting the top of the brush back immediately below the slot therein.

3. A brush structure as defined by claim 1,

characterized by the slot extending completely across the end of the brush back and from side to side thereof providing a flat face at the interior end of said slot, the body portion of the cap completely filling said slot when secured to the back.

4. A brush structure as defined by claim 1,

characterized by opposite faces of the body portion having roughened surfaces for friction retention of the cap in the slot, the roughening comprising regularly arranged teeth, the teeth on opposite surfaces being offset.

WILLIAM C. OTTO.
